Specification for Design.

Patented Mar. 3, 1914.

Application filed October 23, 1913. Serial No. 796,851. Term of patent 3½ years.

To all whom it may concern:

Be it known that I, BURT R. VAN VALKENBURG, a citizen of the United States, residing at No. 3641 West street, Oakland, in the county of Alameda and State of California, have invented a new, original, and ornamental Design for an Orchestrion-Case, of which the following is a specification, reference being had to the accompanying drawing, forming a part thereof.

The figure is a view in elevation of an orchestrion case showing my new design.

What I claim is:—

The ornamental design for an orchestrion case as shown.

In testimony whereof I affix my signature in presence of two witnesses.

BURT R. VAN VALKENBURG.
